CLAIM

I claim the novel design for a handbag and strap design, as shown and described.

DESCRIPTION

FIG. 1 is a top, front and left side perspective view of my new design for a handbag;

FIG. 2 is a front elevational view thereof;

FIG. 3 is a left side elevational view thereof;

FIG. 4 is a rear elevational view thereof;

FIG. 5 is a top plan view thereof; and,

FIG. 6 is a bottom plan view thereof.

The strap is shown broken away in FIGS. 1-5 to indicate indeterminate length.
